UNITED STATES PATENT OFFICE

LOUIS D. GIBSON, OF NORWAY, MAINE, ASSIGNOR TO THE W. F. TUBBS COMPANY, OF NORWAY, MAINE, A CORPORATION OF MAINE

RACKET CHAIR

Application filed October 11, 1928. Serial No. 311,826.

My invention relates to improvements in chairs and relates more particularly to an improved folding chair adapted to be used in camps, boats, automobiles, aircraft and 5 the like.

An object of my invention is to provide a comfortable chair which is strong and light.

Another object of my invention is to provide a comfortable relatively light chair 10 which may be folded for transportation into a very compact space.

Another object of my invention is to provide a chair of the type above indicated which is economical in construction.

15 These and other objects will become apparent from the following description of an embodiment of my invention, illustrated in the accompanying drawings, which form a part of this specification.

20 Referring to the drawings:

Fig. 1 is a side elevational view of a chair embodying my invention.

Fig. 2 is a front elevational view of the chair.

25 Fig. 3 is a vertical, medial, sectional view of the chair, showing the same partially folded.

Fig. 4 is a side elevational view of the chair, folded.

30 Fig. 5 is a front elevational view of the folded chair.

Figs. 6, 7, and 8 are views of different parts of the frame for the chair.

35 Referring to the different figures of the drawings, wherein like parts are designated by like reference characters, I show, therein, a folding chair which comprises generally, a back seat and supports. As best shown 40 in Fig. 8, the seat comprises a U-shaped wood frame strip 2 which is bridged adjacent the ends by a cross slat 3. The cross slat is secured in apertures 4 of the frame strip 2 by screws 5.

45 The back of the chair comprises a generally bowed U-shaped wood frame strip 15, having parallel ends 16 and 17 preferably disposed closer together than are the intermediate portions of the side arm portions 50 18 and 19. The portions adjacent the paral-

lel ends is bridged by a slat 20 in a manner similar to that of the seat.

Both the seat and back frames are provided with a similar webbing filling, which is best shown for the back frame in Fig. 2, being 55 woven onto the frame around the slats 3 and 20, and around the substantially parallel sides 8 and 9, and 18 and 19. Although the material of the webbing and its form may vary within the purview of my invention, I preferably make the webbing of thongs of hide, 60 prepared and treated in substantially the same manner as are the thongs commonly employed for the webbing of snowshoes and I secure the webbing to the wood frame elements in any of the well known ways employed in connection with the securing of 65 webbing to the side frame elements of snowshoes. Preferably the ends of the webbing secured to the forward portion of the seat 70 extend through apertures in the curved portion 10 of the frame at the forward edge of the seat, providing a smooth forward edge on the seat. The same plan may be advantageously followed, as shown, for the rounded 75 top of the back.

A pair of blocks, 12, are secured upon the ends 8 and 9 of the seat frame, as by rivets 13. The side arms of the back are adapted 80 to project downwardly between the side arms 8 and 9 of the seat and are swivelably attached to pivot pins 14 extending transversely through the blocks 12 and the arms 18 and 19. The position of the pins 14, in the blocks 85 12, permits the back to be rotated on the pins to a plane parallel to that of the seat.

As best shown in Fig. 6, a cross slat 22 also bridges the parallel ends 16 and 17 of the back arms and a U-shaped bracing member 23, having pendant arms 24 and 25 secured by their ends to the ends 16 and 17 of the back frame, by means of rivets 26 and 27. The intermediate portion 28 of the bracing member is secured to an intermediate part of the cross slat 22 by rivets 29 and 30.

By virtue of the above construction a very strongly braced back element is provided comprising a U-shaped enclosing frame 15, having pendant side arms 18 and 19 and successively disposed transverse braces 20, 22 100

and 23, the brace 23 being of inverted U-shaped form and forming a truss structure between the ends 16 and 17 of the enclosing frame and the intermediate portion of the bracing slat 22.

5 To the lower side of each arm of the U-shaped seat element is rigidly secured an elongated block 21 by means of wood screws 5 and 31. Hingedly secured by hinges 32 and 33 to each of the blocks 21 are a pair of longitudinally extending laterally disposed chair supports, each support comprising a substantially inverted U-shaped wood strip 34 having an intermediate portion 35 and 10 front and rear pendant arms 36 and 37. The 15 arms of the strip 34 are successively bridged by braces 38 and 39 rigidly secured at their ends to the arms, the brace 37 comprising a tread for the chair and is preferably provided with an outwardly inclined rear end 40. The 20 ends of the arms 36 and 37 preferably project into suitable recesses of the tread and are secured tightly therein in any suitable manner such as by wood screws projected upwardly 25 through the tread into the ends of the arms as indicated, at 41.

Each of the supports comprising the strip 34 and brace 38 and tread 39 is secured by the intermediate portion 35 by the hinges 32 30 and 33 to one of the blocks 21 over a laterally disposed portion of the seat 7 and the hinges are adapted to permit inward swivelling of the supports on the blocks so that the supports can be folded inwardly about the seat 35 while the back is turned on its pivot pins 14 to a position of fortibility.

In Fig. 7 there is illustrated a wood bracing element comprising side pieces 43 and 44 secured in parallel spaced relation between 40 bracing elements 42 and 45, securing elements 46 being suitably projected through the contiguous portions of the elements 42, 43, 44 and 45 to rigidly secure them together. The ends of the side arms 43 and 44 are provided with apertures 47 to permit reduced 45 rounded projections 48 of the brace 42 to extend therethrough. The projections 48 extending laterally of the upper portion of the brace element of Figure 7, is adapted to be 50 projected into suitable journalled recesses extending inwardly from the inner surfaces of the blocks 21 affixed to the bottom of the seat, near the forward portions of such said blocks. By virtue of this arrangement the 55 projecting ends 48 of the bracing element of Fig. 7 is adapted to be swivelably supported from the blocks 21 and therebetween with pendant arms 43 and 44 adapted to take a position between pendant forward arms 36 60 of the hinged chair supports.

U-shaped clips or hooks 50 are secured by the arms 51 to the pendant arms 36 with their side arms extending forwardly to receive between them the ends 52 of the swivelable 65 bracing element of Fig. 7. Similar U-

shaped clips or hooks 53 are secured to the brace 38 for each of the supports with their arms extending rearwardly to receive the pendant ends 36 of the chair back frame strip 15.

70 The projection of the ends 36 of the back into the U-shaped clips 53 of the chair supports and the projection of the bracing element of Fig. 7 by its pendant ends 52 of its side arms into the clips 50 on the supports 75 serves to rigidly hold the supports in spaced relation in vertical position to support the chair during use, at the same time permitting ready readjustment of the parts to the collapsed form illustrated in Fig. 4 for the 80 purpose of transportation.

An additional bracing strip 55 is provided 85 secured onto the top of the blocks 14 and the rear of the seat element side arms, being secured thereto, and is adapted to engage the side parallel ends 16 and 17 of the chair back side arms 18 and 19 when the chair is in the form illustrated in Figure 1 ready for use.

Having described my invention in a specific embodiment I am aware that numerous 90 and extensive departures may be made therefrom but without departing from the spirit of my invention.

I claim:

1. In a folding chair, in combination a 95 back, a seat and a pair of laterally disposed longitudinally extending supports for the seat, said supports being hingedly secured to the seat at each side thereof and adapted for folding thereunder, said back and seat each comprising a substantially U-shaped frame element, brace means extending between and secured to the seat frame arms, said back being pivotally joined at an intermediate portion to the seat arms near their 100 ends, said back adapted to extend within and pendants below the seat frame arms, and hooks secured to the seat supports adapted to detachably secure the pendant portion of the back to the seat supports, said back frame 105 adapted to rigidly space the hinged supports during use of the chair, and said hooks adapted to simultaneously restrain rearward movement of the upper back portion.

110 2. In a folding chair, in combination a back, a seat and a pair of laterally disposed longitudinally extending supports for the seat, said supports being hingedly secured to the seat at each side thereof and adapted for folding thereunder, said back and seat each comprising a substantially U-shaped frame element, brace means extending between and secured to the seat frame arms, said back being pivotally joined at an intermediate portion to the seat arms near their ends, said 115 back adapted to extend within and pendants below the seat frame arms, and hooks secured to the seat supports adapted to detachably secure the pendant portion of the back to the seat supports, said back frame adapted 120 to the seat supports, said back frame adapted 125 to the seat supports, said back frame adapted 130 to the seat supports, said back frame adapted 135

to rigidly space the hinged supports during use of the chair, and said hooks adapted to simultaneously restrain rearward movement of the upper back portion, and a front bracing element adapted to be disposed between and brace the supports in operative position, said bracing element hingedly secured to the bottom of the seat forwardly of the back and having laterally disposed pendant portions 10 interposed between the supports and adapted to prevent inward movement of the supports.

3. In a folding chair, in combination a back, a seat and a pair of laterally disposed longitudinally extending supports for the 15 seat, said supports being hingedly secured to the seat at each side thereof and adapted for folding thereunder, said back and seat each comprising a substantially U-shaped frame element, brace means extending between and 20 secured to the seat frame arms, said back being pivotally joined at an intermediate portion to the seat arms near their ends, said back adapted to extend within and pendantly below the seat frame arms, and hooks secured to the seat supports adapted to detachably secure the pendant portion of the back to the seat supports, said back frame adapted to rigidly space the hinged supports during 25 use of the chair, and said hooks adapted to simultaneously restrain rearward movement of the upper back portion, each of said supports comprising a substantially inverted U-shaped frame element and a longitudinally extending chair tread bridging the ends of 35 the said element.

4. In a folding chair, in combination a back, a seat and a pair of laterally disposed longitudinally extending supports for the seat, said supports being hingedly secured to 40 the seat at each side thereof and adapted for folding thereunder, said back and seat each comprising a substantially U-shaped frame element, brace means extending between and secured to the seat frame arms, said back being pivotally joined at an intermediate portion to the seat arms near their ends, said back adapted to extend within and pendantly below the seat frame arms, and hooks secured to the seat supports adapted to detachably secure the pendant portion of the back to the seat supports, said back frame adapted to rigidly space the hinged supports during 45 use of the chair, and said hooks adapted to simultaneously restrain rearward movement of the upper back portion, and a back and seat filling comprising a webbing of hide thongs.

5. In a folding chair, in combination a back, a seat and a pair of laterally disposed longitudinally extending supports for the seat, said supports being hingedly secured to the seat at each side thereof and adapted for folding thereunder, said back and seat each comprising a substantially U-shaped frame element, brace means extending between and

secured to the seat frame arms, said back being pivotally joined at an intermediate portion to the seat arms near their ends, said back adapted to extend within and pendantly below the seat frame arms, and hooks secured to the seat supports adapted to detachably secure the pendant portion of the back to the seat supports, said back frame adapted to rigidly space the hinged supports during use of the chair, and said hooks adapted to simultaneously restrain rearward movement of the upper back portion, and a brace for the ends of the seat frame arms extending transversely therebetween, disposed rearwardly of the swivelling axis of the back and seat and engageable by the back when the chair is in use to reenforce it against rearward movement.

6. In a folding chair, in combination a back and a seat, of a pair of longitudinally extending lateral supports for the seat hinged to the sides thereof and adapted to be folded inwardly thereunder, said back comprising upper and lower portions hinge connectors disposed intermediate said back portions for hingedly supporting the back on the seat near its rear end, said back adapted to fold with its upper portion superposed over said seat and alternately with its upper portion in an upright position of use with its lower portion extending pendantly below said seat, connecting means adapted to detachably secure the pendant portion of said back to said pair of hinged seat supports to simultaneously maintain the seat supports in seat supporting position, and said back in its said upright position of use.

7. In a folding chair, in combination a pair of hingedly joined U-shaped back and seat elements, the lateral arms of the back element projecting beyond the hinging axis of said elements, a pair of parallel pendant seat supports hingedly connected to the lateral arms of the seat, means whereby the projecting ends of the back arms may have interlocking engagement with said seat supports to hold them in operative spaced relation.

8. In a folding chair, in combination a pair of hingedly joined U-shaped back and seat elements, the lateral arms of the back element projecting beyond the hinging axis of said elements, a pair of parallel seat supports, pendantly hingedly connected to the lateral arms of the seat and means whereby the rearward movement of the joined ends of said back arms is limited relative to said seat, and spacing means pendantly supported by said seat arms forwardly of their joined ends having interlocking engagement with hooks on said supports to operatively space said supports.

In testimony whereof I hereunto affix my signature this 11th day of September, 1928.
